Primary Examiner — Keith J Wilson(57) **CLAIM**

The ornamental design for a sanitizing fogger, as shown and described.

DESCRIPTION

FIG. 1 is a front-top perspective view of a sanitizing fogger showing my new design;

FIG. 2 is a front-bottom perspective view thereof;

FIG. 3 is a front elevational view thereof;

FIG. 4 is a rear elevational view thereof;

FIG. 5 is a left elevational view thereof, where the right elevation view is mirrored thereto;

FIG. 6 is a top plan view thereof; and,

FIG. 7 is a bottom plan view thereof.

The broken line showing of the claim is included for the purpose of illustrating portion of a sanitizing fogger and forms no part of the claimed design.

1 Claim, 7 Drawing Sheets(56)
